GUN GAME

John F. Eakins, Evanston, Ill., assignor to Albert
G. McCaleb, Evanston, Ill.

Application December 30, 1936, Serial No. 118,211

2 Claims. (Cl. 273—101.1)

This invention relates to a gun game apparatus of the type in which a flash of light is directed by a gun to a target associated with a photoelectric cell which, when energized by a correctly aimed flash, actuates indicating devices which indicate the efficiency of the marksman.

In accordance with the present invention I provide an improved game of this type in which a plurality of targets are energized continuously in sequence, the energization being arranged in an irregular order so that the marksman is always required to shoot at a target which is presented unexpectedly. Each target is energized for a limited time only so that the conditions of real sport are duplicated to a considerable extent. The energization of a target is indicated by the illumination of a lamp associated therewith. Each target has a photoelectric cell which is operatively connected to the remaining apparatus only when the circuit of its associated lamp is completed.

The game apparatus comprises sound means responsive to a successful shot, visual means for indicating the number of successful shots and other features which will hereinafter be fully described with reference to the embodiment of the invention shown in the accompanying drawings, in which:

Figure 1 is a perspective view showing the game apparatus;

Fig. 2 is a diagrammatic view and wiring diagram;

Fig. 3 is a sectional detail view showing the switch drum construction, the section being taken on the line 3—3 of Fig. 4;

Fig. 4 is a sectional detail view, taken on the line 4—4 of Fig. 3;

Fig. 5 is an expanded view of the periphery of the switch drum on a smaller scale, and

Fig. 6 is a fragmentary plan view of the coin slide.

Referring to the drawings, the reference numeral 10 designates a cabinet located at the butt of the range. This cabinet serves as a support for the gun 11 when the same is not in use. The gun is secured to the cabinet 10 by means of a cable 12, which includes a plurality of conductors which will hereinafter be described. Upon the cabinet 10 is a coin slide 13 of known type. When a coin of the appropriate denomination is inserted by means of the coin slide 13, the apparatus is freed to the extent of a certain number of shots. In the present embodiment of the invention there are five targets 14 and five shots are permitted for each coin. It will be un-

derstood, however, that this precise number of targets or shots is quite arbitrary and that the apparatus may be designed for any desired number, either of targets or of shots permitted for the payment of one coin.

The targets 14 may be formed to simulate flying ducks, or any other appropriate form of target may be employed. The targets 14 may suitably be transparent figures arranged upon a black background on a sheet of glass 15. The sheet of glass 15 may suitably form the front wall of a box-like frame 16 which may, for example, be supported on a wall. Within the box-like frame 16 are provided housings 17, one for each of the targets 14. Each housing 17 includes an incandescent lamp 18 and a photoelectric cell 19. The photoelectric cell 19 is enclosed within a housing 20 so that it is not illuminated by the lamp 18.

The housing 20 comprises a forwardly projecting tubular portion 21 which is directed outwardly towards the target 15. When the lamp 18 of a target is illuminated, the whole target is seen as a bright object with the exception of a portion corresponding to the tube 21, which is dark and serves as the object to be aimed at. Also contained within the box-like frame is a sound producing device 22 of the general form of a bellows, provided with a reed structure 23 which is caused to emit a sound when the bellows is contracted. The bellows is adapted to be contracted by the movement of an armature 24 into a solenoid 25 when that solenoid is energized. The bellows 22 may include a spring 26 which tends to return the bellows to initial position when the solenoid 25 is no longer energized.

The gun 11 comprises a barrel 27 through which light is adapted to be projected from an incandescent lamp 28 located within the gun. A lens 29 may be located in the barrel 27 so as to concentrate the beam of light into small compass. The trigger 30 controls a switch 31 of any suitable type which is adapted to open automatically almost immediately after it is closed by the trigger 30. The switch 31 and lamp 28 are in series and are provided with leads 32 and 33 which are located within the cable 12. The cabinet 10 is connected to the box-like frame 16 by means of a cable 34 and electric energy may be supplied to the cabinet 10 by means of leads 35 and 36 from any suitable source.

The remainder of the apparatus is located within the cabinet 10. Thus, a switch drum 37 is rotatably mounted within the cabinet 10. This drum may be of any suitable construction, but it is preferred to construct it as shown in Figs. 3

and 4. As shown in these figures, the drum comprises a peripheral member 38 upon which is carried a cylinder of insulation 39. A metal sleeve or cylinder 40 is mounted over the cylinder 39 and a cylinder 41 of insulation is mounted over the metal cylinder 40. Five series of contacts 42 are mounted on the cylinders 41 so that they lie substantially flush therewith. The contacts 42 may preferably be integral with the metal cylinder 40 and may be formed from portions which are cut out of the cylinder 40 and are bent as shown in Fig. 3.

The cylinder 41 is provided with openings through which the contacts 42 pass. The contacts 42 are arranged in five circumferential series 15 and they are staggered in such a way that their succession is irregular. Thus, referring to Fig. 5, it will be seen that if the contacts 42 are numbered consecutively in the downward direction, then they are presented in the circumferential direction of the drum 37 in the following order: 20 5, 1, 5, 4, 2, 3, 2, 4, 1, 5, 3, 4, 5, 1, 3, 2, 4, 1, 5, 3, 2, 3, 2, 4. The consecutive contacts 42 are arranged so that they do not overlap in the circumferential direction of the drum. These contacts are adapted to be engaged by five brushes 43 the contacting portions of which are in a line parallel to the axis of the drum. The contacts 42 are preferably of such length that there is always one of them in contact with one of the brushes 43.

I provide a drive for the drum 37 whereby it is rotated slowly all the time that the game is in operation. This means may suitably comprise an electric motor 44 which drives the drum 37 by means of a gear reduction 45.

Upon the coin slide 13 is pivotally mounted a laterally projecting dog 46 which is pressed against a stop by a coil spring 47. When the coin slide 13 is forced inwardly, the dog 46 strikes the upper end of an arm 48 pivotally mounted on a stationary pivot. A spring 49, secured to the arm 48, tends to hold the same in the position shown in Fig. 2 against a stop 50. When the coin slide 13 approaches the innermost end of its stroke, as shown in dash and dot lines in Fig. 2, the dog 46 clears the arm 48 so that it may resume its normal position under the influence of the spring 49. When the coin slide 13 is then pulled outwardly again, the dog 46 slips past the end of the arm 48. When the arm 48 is thus moved inwardly by the coin slide 13, it is brought into engagement with a lever 51 in such a manner that the lever 51 is displaced to the left, as viewed in Fig. 2.

The cabinet 10 also contains two counting devices 52 and 53. The counting device 52 is a main switch mechanism which regulates the number of shots which may be fired for each coin. It comprises a ratchet wheel 54 which is biased in the clockwise direction, as viewed in Fig. 2, by a spring 55. The ratchet wheel 54 rigidly carries a switch arm 56 which is adapted to cooperate with contacts 57 which are connected in series. In the embodiment of the invention illustrated, five shots are permitted for one coin and, consequently, there are five contacts 57 corresponding to five positions of the switch arm 56.

The lever 55 carries a pawl 58 which cooperates with the ratchet wheel 54 and is adapted to prevent rotation of this ratchet wheel under the influence of the spring 55. When, however, the lever 51 is displaced by the arm 48 in the manner hereinbefore described, the pawl 58 is moved away from the ratchet wheel 54 and, conse-

quently, the spring 55 moves the ratchet wheel 54 and the switch arm 56 into the dotted line position shown in Fig. 2, at which position they are arrested by a stop 59. In this position the switch arm 56 is in engagement with the first contact 57.

The lever 51 is held in its normal position by a spring 60. A lever 61 is pivotally mounted adjacent the ratchet wheel 54 and carries a detent 62. The lever 61 is normally held in the position shown in Fig. 2 by means of a spring 63 with the detent 62 out of engagement with the ratchet wheel 54. The armature 64 of a solenoid 65 is pivotally connected to the lever 61. When the solenoid 65 is energized, the lever 61 moves downwardly and engages the ratchet wheel 54, causing it to rotate so as to move the switch arm 56 one step—that is, from one contact 57 to the next contact. The last step moves the arm 56 away from all the contacts 57 and the circuit of the machine is broken, as will hereinafter be described.

The lever 51 is connected by a link 66 to another pivoted lever 67. This lever carries a pawl 68 which cooperates with a ratchet wheel 69 of the counting mechanism 53 in the same manner as the pawl 58 cooperates with the ratchet wheel 54. A switch arm 70 is rigidly carried by the ratchet wheel 69 and is adapted to reach an initial position determined by a stop 71 under the influence of a spring 72, when the lever 67 is moved simultaneously with the lever 51 on the insertion of a coin and the actuation of the coin slide 13. The ratchet wheel 69 is adapted to be rotated step by step in the opposite direction—that is, the clockwise direction, as viewed in Fig. 2, by means of a detent 73 carried by a pivoted lever 74. The pivoted lever 74 is actuated by a solenoid 75, the armature 76 of this solenoid being pivotally connected to the lever 74. The detent 73 is normally held out of engagement with the ratchet wheel 69 by a spring 77.

The switch arm 70 is adapted to cooperate with contacts 78 which are of the same number as the number of shots permitted by the insertion of each coin. In this embodiment that number is five. When the lever 61 is swung in the manner described, the spring 72 throws the switch arm 70 into the position shown in dotted lines in Fig. 2. When the solenoid 75 is energized, which occurs when the marksman makes a hit, the arm 70 is moved into engagement with the first contact 78. At each successive hit the arm 70 is moved into engagement with the next contact 78. Each of the contacts 78 is connected to a signal lamp 79, these lamps being suitably arranged on the cabinet 10 so as to indicate visually the number of hits which have been made by the marksman. The cabinet 10 also includes an amplifier 80 which is connected in the manner hereinafter described.

The power line 35 is connected directly to the amplifier 80 to supply energy thereto. The power line 36 is connected through electromagnets 81 to the lamps 79. The other terminals of these lamps are connected individually to the brushes 43. The power line 36 is also connected through pole 82 and pole 83 of a double pole switch to the solenoid 25 and the solenoid 75, respectively. The other terminals of these solenoids are connected to the power line 35. The power line 36 is connected to the switch arms 56 and 70. The contacts 57 are connected to one terminal of the motor 44 and to a brush 85 which is in continual engagement with the

cylinder 40 of conductive material and, consequently, with the contacts 42, one of which is always in engagement with one of the brushes 43. The contacts 57 are also connected to the lead 32 previously referred to and to the other power terminal of the amplifier 80. The power line 35 is connected to terminals of the signal lamps 79 and to one terminal of the solenoid 65.

The output of the amplifier 80 is connected to an electromagnet 85 which is adapted, when energized, to move the poles 82 and 83 to closed position. One conductor 86 of the input circuit of the amplifier is connected to each of the photoelectric cells 19. The other terminals of these cells are connected through switches 87 to the other line 88 of the input circuit of the amplifier. The switches 87 are associated with the electromagnets 81, each switch 87 being associated with the electromagnet 81 in series with the lamp 18 which is associated with the particular photoelectric cell 19 controlled by that switch 87. A time delay switch 89 is inserted in the line 32 so as to prevent operation of the gun until the tubes of the amplifier have warmed up to operating temperature.

The operation is as follows. Initially, the position of the main switch arm 56 is that shown in Fig. 2. The switch arm 70 is normally found in a position indicating the score of the last player. Thus, it is shown in a position which completes the circuit through the third lamp 79, indicating the previous marksman has made three hits. The circuit is completed from power line 36, switch arm 70, third contact 78, third lamp 79 and power line 35. To free the apparatus for shooting it is necessary to insert a coin in the coin slide 13 and to push the coin slide inwardly into the position indicated in dotted lines in Fig. 2. In so doing the upper end of the arm 48 is pushed to the right, as viewed in that figure, and it is released so that it returns to its initial position under the influence of the spring 49.

The movement of the arm 48 displaces the lever 51, with the result that the pawls 58 and 68 are withdrawn from their ratchet wheels and these wheels rotate under the influence of their springs so as to bring the switch arm 56 into engagement with the first of the contacts 57 and the switch arm 70 out of engagement with all the contacts 78. The particular lamp 79 which was illuminated now goes out and the main switch constituted by the switch arm 56 completes a circuit through the particular lamp 18 associated with the brush 43 which is in engagement with one of the contacts 42. The completion of the energization of this lamp circuit energizes the associated electromagnet 81 and closes the switch 87 which connects the photoelectric cell 19 associated with that particular lamp 18 to the amplifier 80. When the main switch arm 56 closes the main circuit, the power circuit of the amplifier 80 is completed and the tubes warm up. The motor 44 starts immediately and continues its operation until the main circuit is again broken by the arm 56.

After the tubes of the amplifier 80 have warmed up, the delay switch 89 closes and the gun can now be aimed and operated so as to project a flash. If the marksman directs the gun correctly, the projected flash impinges upon the photoelectric cell 19 of the particular object which is energized. That energization is indicated to the marksman by the illumination of one of the objects. When the marksman pulls

the trigger to illuminate the lamp 28, the circuit through the lamp is completed through the solenoid 65. Each time the solenoid 65 is energized, the switch arm 56 moves step by step in the clockwise direction, as viewed in Fig. 2. When five shots have been fired the switch arm 56 moves away from all of the contacts 57 and the main circuit of the apparatus is open and the apparatus cannot be used until a further coin is inserted by the coin slide 13.

If the marksman is successful in his aim, the input circuit of the amplifier receives an impulse from the photoelectric cell, which impulse is amplified and is sufficient to energize the electromagnet 85, closing the circuits through the solenoid 25 and the solenoid 75. The energization of the solenoid 25 operates the bellows 22, which causes the emission of a sound to indicate a hit. The energization of the solenoid 75 causes the switch arm 70 to move one step in the clockwise direction, as viewed in Fig. 2. Consequently, when the first hit is made, the first lamp 79 becomes illuminated, when the next hit is made the second lamp 79 is illuminated, and so on. After the gun has been fired five times, the game becomes inoperative as hereinbefore described, and the score of the marksman is indicated by the particular lamp 79 which is then illuminated.

It will thus be seen that I have provided an apparatus in which a plurality of targets is energized in succession, the order of succession being unknown to the marksman in advance. Furthermore, my apparatus provides for the presentation of new targets in succession for the marksman to aim at. Thus, the marksman is only allowed a certain predetermined period of time in which he must hit a target, thus simulating the conditions of real sport to a considerable extent.

Although the invention has been disclosed in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. In a gun game, in combination, a plurality of targets having stationary positions, an incandescent lamp associated with each target, a photoelectric cell associated with each target, an amplifier, means for energizing any one of said lamps, means controlled by the lamp current for connecting the associated cell to the amplifier, said energizing means including switching mechanism, and means continuously and automatically operating said switching means to energize the lamps in sequence.

2. In a gun game, in combination, a plurality of targets having stationary positions, an incandescent lamp associated with each target, a photoelectric cell associated with each target, an amplifier, switching means for energizing any one of said lamps, means controlled by the lamp current for connecting the associated cell to the amplifier, an electric motor for continuously operating said switching means to energize the lamps in sequence, a gun adapted to project flashes toward said targets, coin released mechanism permitting the operation of the gun for a definite number of times and effective to stop the motor, and means operated by the amplifier for indicating the number of hits.
